UNITED STATES PATENT OFFICE.

CUMBERLAND MASSIE AND JOSIAH LEGAN, OF LONG LANE, MISSOURI.

CHURN.

SPECIFICATION forming part of Letters Patent No. 275,059, dated April 3, 1883.

Application filed December 29, 1882. (No model.)

To all whom it may concern:

Be it known that we, CUMBERLAND MASSIE and JOSIAH LEGAN, citizens of the United States of America, residing at Long Lane, in the county of Dallas and State of Missouri, have invented certain new and useful Improvements in Churns, of which the following is a specification, reference being had therein to the accompanying drawings.

10 This invention pertains to improvements in churns, and has reference more especially to the dasher, its object being to facilitate the churning operation or processs and to effect the thorough conversion of the cream; and it 15 consists in the construction of the dasher with an approximate pyramidal-shaped "crown" or deflector fastened to the staff or shaft, with parallel apertured or perforated bars arranged upon the staff below the crown, and with 20 hinged or vibrating wings or beaters hung upon the parallel bars and controlled as to movement by stops disposed above said wings or beaters and upon the sides of the said bars, substantially as hereinafter more fully set forth and claimed.

25 In the accompanying drawings, Figure 1 is a sectional elevation of the churn, and Fig. 2 is a detailed perspective view of the dasher. Fig. 3 is a sectional view of the same.

30 In carrying out our invention we employ a suitable cream receptacle or vessel, A, preferably cylindric in the present instance, and supported in a frame, B, with divergent legs resting on the floor or ground to hold it steady 35 during the churning operation.

To an upwardly-extending arm or bracket, a, of the frame B is pivoted or articulated the lever or handle C, connected to the upper end of the dasher staff or shaft D. The staff or 40 shaft D passes through and works up and down in an elongated slot in the cover b of the receptacle or vessel A, its lower end extending to near the bottom of the said receptacle, where it is provided with the dasher, the construction of which is as follows:

45 E is an approximate pyramidal - shaped crown or deflector, affixed at its apex to the staff or shaft, the latter passing through it; also secured to the staff, a short distance below the deflector, are parallel perforated or apertured bars F, arranged edgewise to the deflector, a space, F', being left between them, the function of which will be presently understood. This space or passage is provided by 50 arranging them on opposite sides of the staff.

G G are wings or beaters, each being preferably semicircular in shape, which are hinged, so as to have a vibrating action when the dasher is in operation, at their straight edges to the sides of the parallel bars F. These 60 wings or beaters are limited in their upward movement by cross-pieces or stops c, fastened to the upper edges of the bars F and projecting beyond the upper edges of the wings, their downward and inward movement being governed by the cleats or stops c' c', the latter being inclined, with the slant outward toward their lower ends, to prevent the closing up the perforations in the bars F by the wings at any time.

70 It will be noticed that the action of the wings or beaters G upon the cream during the downward stroke or movement of the staff or shaft is to force it (the cream) through the apertures or perforations of the parallel bars F, 75 breaking the globules up between said bars or through the passage F' and into and against the deflecting-surface of the crown or deflector E, still further acting upon and comminuting the globules of cream. From the deflector 80 or crown E, during the upward movement of the dasher staff or shaft, the partially-churned cream passes down through the passage F', while by the same movement of the staff or shaft the action of the wings G upon 85 the cream causes it to be forced against the sides of the receptacle or vessel, which further reduces the globules of cream and effects the thorough conversion of the cream, while it also facilitates the churning process or opera- 90

95 Having thus fully described our invention, we claim and desire to secure by Letters Patent—

A churn-dasher consisting of the approximate pyramidal-shaped crown or deflector E, the perforated or apertured parallel bars F, with a space or passage, F', between them, said parts being secured to the staff or shaft D, and of the hinged or articulated wings or 100 beaters G, and the stops c, connected to the parallel bars F, as shown and described.

In testimony whereof we affix our signatures, in presence of two witnesses, this the 20th day of December, 1882.

CUMBERLAND MASSIE.
JOSIAH LEGAN.
